Specification for Design.

Patented Nov. 15, 1921.

Application filed March 30, 1921. Serial No. 457,058. Term of patent 3½ years.

To all whom it may concern:

Be it known that I, ARTHUR J. LAWS, a citizen of the United States of America, residing at Lakewood, in the city of Cleveland, county of Cuyahoga, and State of Ohio, have invented a new, original, and ornamental Design for a Medallion, of which the following is a specification, reference being had to the accompanying drawing, forming a part thereof.

And Fig. 2 is a view of the reverse of said medallion.

I claim:

The ornamental design for a medallion, as shown.

In testimony whereof I do now affix my signature.

ARTHUR J. LAWS.
